[57] CLAIM

The ornamental design for a drawer pull, as shown and described.

DESCRIPTION

FIG. 1 is a perspective view of the drawer pull showing our new design wherein a drawer face is shown in broken lines for illustrative purposes only and does not form a part of the claimed design;

FIG. 2 is a front elevational view thereof;

FIG. 3 is a back elevational view thereof;

FIG. 4 is a top view thereof;

FIG. 5 is a bottom view thereof; and,

FIG. 6 is a left side view thereof, the opposite side being a mirror image.
